UNITED STATES PATENT OFFICE.

FREDERICK W. HEDGELAND, OF CHICAGO, ILLINOIS, ASSIGNOR TO THE
W. W. KIMBALL COMPANY, OF SAME PLACE.

FOLDING KEY-BOARD FOR ORGANS.

SPECIFICATION forming part of Letters Patent No. 469,242, dated February 23, 1892.

Application filed November 20, 1891. Serial No. 412,473. (No model.)

To all whom it may concern:

Be it known that I, FREDERICK W. HEDGELAND, a citizen of the United States, residing in Chicago, in the county of Cook and State 5 of Illinois, have invented a new and useful Improvement in Folding Key-Boards for Organs, of which the following is a specification.

A folding key-board has been heretofore devised and made by me, and with it a section 10 of the case-front above the stops has been hinged in such manner as to adapt it to move out of the way of the stops when the board is folded up. As the parts have been constructed and arranged, the hinged section 15 of the case has been made to yield when the key-board is closed into or against the case and give room to the knobs or pulls of the stops and the stop-board by power received from the stop-board, the latter swinging with 20 the key-board in the folding movement. As heretofore constructed and arranged, the stop-knobs have caused difficulty in the folding and unfolding movements by scratching or marring the hinged portion of the case, which 25 they are very liable to do, especially if any of them stand out of line and do not, when pushed in, occupy their proper positions. To obviate these objections, I place a circular guard upon the stop-board, which projects 30 outwardly a sufficient distance to enable it to lift the hinged front and prevent all contact between it and the draw-stops. This guard being circular in its outline creates no perceptible amount of friction and obviates the 35 scratching and marring referred to.

In the drawings I have shown at Figure 1 a section of an organ having a folding key-board, to which my invention has been applied, showing the key-board lowered for use; 40 and at Fig. 2, a like section showing the key-board folded up.

In said drawings, A represents the keys of the manual, B the front board, and C a bottom board, the same constituting the key-board of the instrument and hinged to the case at c. Above the keys A is the stop-board D', in which are the draw-stops D, (only one of several being shown,) provided with pulls or knobs d. The parts all fold up and open 45 simultaneously, though the stop-board turns upon a different center from the key-board, its axis being upon the line of the pivot of the joint d' in the stop D. The dotted lines, 50

Fig. 1, show the relative movements of the key and the stop boards. Above the stop-board is the hinged front E, forming a part of the front of the case. It is supported upon a hinged joint e so it may swing up and inward and make room for the stop-board, as shown at Fig. 2, the bottom board C then 60 forming a surface flush with the adjoining portions of the case.

To avoid the marring of the front E by the pulls d, as well as by other parts of the stop-board, I apply to the stop-board a circular 65 guard F, which may be conveniently made of wire, and the circular plane of which is outside of the plane of the pulls, as clearly illustrated. This guard may be applied to the stop-board at one end, so that it will not interfere with the player in his use of the stops. It operates to lift the falling front section 70 when the key and stop boards are raised and holds said section up so that there is no contact with it by the stops or other portions of 75 the folding boards.

A board M, laid over the keys, acts as a lock to prevent the raising of the key-board, and the case-section serves a similar function with the stop-board, so that when the boards 80 are to be folded up the case-section must be first swung backward, and the front of the stop-board be then lifted so as to free it from board M.

I have shown in the drawings an octave- 85 coupling mechanism adapted to be used with my folding key-board; but I lay no claim to the same in this application, as I purpose filing another application immediately to protect my interest in such coupling mechanism. 90

I claim—

1. The combination, with the folding stop-board and the hinged case-section, of a guard adapted to lift the case-section when the board is folded and prevent interference with 95 the stops, substantially as specified.

2. The combination, with the folding key and stop boards, of a hinged case-section E and a guard F, carried by said boards and acting to lift said case-section when said 100 boards are folded, substantially as specified.

FREDERICK W. HEDGELAND.
